CIGARETTE DISPENSER

Filed July 2, 1947

UNITED STATES PATENT OFFICE

2,479,340

CIGARETTE DISPENSER

Edward G. Gantner and David James, Chicago,
Ill., assignors to Gantner Industries, Inc., Mor-
ton Grove, Ill., a corporation of Illinois

Application July 2, 1947, Serial No. 758,586

9 Claims. (Cl. 312—79)

1

This invention relates to a cigarette dispenser and more particularly to a device for mounting at accessible places in an automobile and the like for dispensing a single cigarette at a time.

Former cigarette dispensers of this type of which we are aware, have not been sufficiently dependable. There has been too great a tendency either for the cigarettes to jam or otherwise fail to be dispensed.

According to this invention there is provided a dispensing device which is particularly constructed to avoid these difficulties. Said device in one embodiment comprises a drawer adapted to slide into and out of a housing with some friction. The drawer is provided with an inclined false bottom which is slideable on tongues carried by the rear of the drawer. At the lower front of the false bottom is a cigarette receiving recess which is adapted to expose a single cigarette without the drawer when said false bottom is pulled out. A catch is provided at the rear of the drawer to hold the false bottom in non-dispensing position.

The recessed false bottom portion is so formed as to engage the bottom of the drawer just prior to closure of the false bottom, so that the inclined false bottom is positively jarred to move another cigarette into the recess when the false bottom is in fully closed position. Furthermore the catch is so formed in relation to the false bottom as to further jar the false bottom, this time from the rear, so as to insure that a cigarette will fall into the recess. A further agitation is achieved by virtue of the false bottom sliding under the cigarettes to be dispensed.

The dispenser is so designed as to be capable of being economically formed from a few pieces of sheet material stamped into the component part of the device. For loading of cigarettes it is merely necessary to pull out the drawer from the housing and place the cigarettes upon the false bottom. To cleanse the drawer, it is simply removed from the housing.

It is therefore an important object of this invention to provide a cigarette dispenser which will positively dispense one cigarette only and will not jam or otherwise fail.

It is a further important object of this invention to provide a dispenser which may be economically stamped from a few pieces of sheet material and easily assembled.

It is a still further object of the invention to provide a dispenser which may be easily refilled and readily cleansed.

It is a more specific object of the invention to

2

provide a false bottom for receiving a single cigarette which is positively refilled by jarring the false bottom at the front and rear thereof, and by virtue of its undermining action, all occurring automatically as the false bottom is pushed back into its housing.

Other and further important objects of this invention will be apparent from the disclosures in the specification and the accompanying drawings.

On the drawings:

Figure 1 is an isometric view of a cigarette dispenser embodying the principles of our invention in nondispensing position;

15 Figure 2 is a longitudinal sectional view through the dispenser of Figure 1 showing the dispenser in nondispensing position;

Figure 3 is a longitudinal sectional view showing the dispenser in dispensing position;

20 Figure 4 is a longitudinal sectional view showing dispenser false bottom in partially closed position;

Figure 5 is a longitudinal sectional view showing the dispenser in position for loading of cigarettes therein; and

25 Figure 6 is a cross sectional view taken substantially along the line VI—VI of Figure 2.

The reference numeral 10 designates generally a cigarette dispenser which may be stamped from sheet material, such as sheet metal and is adapted to be placed at convenient locations within an automobile and the like, as on an arm extending from the steering post of the automobile.

The device illustrated comprises a generally U-shaped housing 11 having inturned legs 12 to provide a channel for receiving a box-like tray or drawer 13. The side walls of the housing preferably converge slightly toward their free ends to tightly hold the drawer. The bottom 14 of tray 13 rides on the legs 12 and forms the bottom of the dispenser. This housing may be eliminated if a similar housing is formed in a wall in which the device is to be carried.

45 The side walls of the drawer 13 are illustrated as of less height than the housing side walls to reduce friction and save material. Front wall 15, however, extends to the top of the housing in closed position of the drawer in order to provide a neat uniform appearance and is spaced from the bottom of the drawer to provide an opening 16, through which a false bottom or tray 17 is adapted to slide.

40 The housing may be stamped from a single piece of sheet material and drawer may also. 50 The front wallpiece may be separate if desired

and might fold rearwardly to indicate the height to which cigarettes may be placed within the drawer and to provide a more complete closure. The rear wall of the drawer includes a forward piece 20 having a pair of tongues 18 and a catch 19 struck out therefrom. The ends of the tongues are turned down to provide flanges 21. The false bottom 17 may be formed from a single strip of sheet material approximately the width of the drawer and having a downturned flange 22 at its rear end. This flange 22 is provided with a pair of rectangular openings 23 slidably receiving the tongues 18 (Figure 6). As will be seen in Figure 5, the two flanges 21 and 22 will engage to limit outward movement of the false bottom 17 relative to drawer 13. The sides of the housing will hold the drawer within until an added force is exerted whereupon the drawer is withdrawn from the housing. The false bottom handle 24 thus serves both to manipulate the cigarette dispensing false bottom and also serves to pull out the drawer upon additional effort.

The false bottom flange 22 is of such length as to engage a forward inclined portion of catch 19 just prior to full closure of the false bottom. The flange 22 slides up the inclined portion depressing the catch and forcing the flange upwardly. A sudden dip 25 allows the flange to drop and the catch to snap upwardly, resulting in a sudden jarring of the false bottom.

The forward end of the false bottom 17 has a groove or channel 26 for receiving a single cigarette only, and forwardly of said groove the false bottom is curled upon itself to form the handle 24. The space between the underside of groove 26 and the main inclined surface of the false bottom is partially filled as indicated at 28 to facilitate the retraction of the part 17 into the casing; however as best seen in Figure 4, there is still a sudden engagement between the bottom 14 of the drawer and the undersurface of groove 26.

The operation of our dispenser is as follows: To load the device with cigarettes, the handle 24 is pulled until the false bottom flange 22 engages flange 21 of the tongues 18; the drawer 13 is then pulled out by exerting an additional effort on the handle 24 and cigarettes indicated by the reference numeral 29 inserted therein.

In operation when the false bottom is pushed back into the drawer, the false bottom is jarred by the engagement of the groove underside and the bottom of the drawer and by the false bottom flange 22 and catch 19. Further agitation of the cigarettes may occur due to the undermining action of the false bottom sliding upwardly on tongues 18. The end result is that a single cigarette will roll into the groove as shown in Figure 2, after the drawer is pushed back into the housing and thus a single cigarette will be dispensed each time the false bottom is pulled open as shown in Figure 3.

It will be apparent that, for cleaning of the device, it is merely necessary to pull the drawer entirely out of the housing.

The assembly of the device might be as follows: After the false bottom rear flange 22 and tongues 18 are engaged, the tongue and catch carrying piece 20 may be inserted in the drawer and attached to the drawer as by welding indicated by the reference numeral 30. The front wall piece 15 may then be fixed at the proper distance from the bottom of the drawer. Struck out portions 31 of the tongue carrying piece 20 are covered by the rear wall of the drawer and

the front wall extends to the top wall of the drawer, so that in closed position of the drawer and false bottom, the device is substantially completely closed about the cigarettes.

It will, of course, be understood that various details of construction may be varied through a wide range without departing from the principles of this invention and it is, therefore, not the purpose to limit the patent granted hereon otherwise than necessitated by the scope of the appended claims.

We claim as our invention:

1. A cigarette dispenser comprising a housing, a drawer, slidable into and out of said housing, a false bottom for said drawer comprising an inclined sheet of material slidably mounted in the drawer for receiving cigarettes thereon, said false bottom sheet having a cigarette receiving groove at the forward lower end thereof, a tongue and a catch formed at the upper rear of said drawer, said tongue engaging the upper rear end of said false bottom sheet for guiding the same into and out of said drawer and limiting the movement thereof, a projection on said false bottom sheet engaging said drawer prior to full closure of said false bottom for jarring a cigarette into the groove, and an abutment surface on said false bottom sheet engageable by said catch at full closure of said false bottom sheet, said catch also acting to jar said false bottom sheet.

2. A cigarette dispenser comprising a housing, a drawer slidable into and out of said housing for receiving cigarettes in its open position, a false bottom for said drawer comprising an inclined strip of material slidably mounted in the drawer for receiving cigarettes thereupon, said false bottom strip having a cigarette receiving groove at the forward lower end thereof and a depending flange at the rear end, a tongue extending inwardly from the upper rear end of said drawer and having a lateral projection at the end thereof, said flange formed at the rear end of said false bottom strip having an opening therein for receiving said tongue slidably therethrough, said false bottom flange and tongue projection engaging to limit opening movement of said false bottom, a catch formed at the upper rear end of said drawer and engaging said false bottom flange just prior to full closure of said false bottom to jar the same to move a cigarette into said groove, and a projection on said false bottom strip engaging said drawer just prior to full closure of said false bottom to further agitate said cigarettes.

3. A cigarette dispenser comprising a housing, a drawer slidable into and out of said housing for receiving cigarettes in its open position, a false bottom for said drawer comprising an inclined strip of material slidably mounted in the drawer for receiving cigarettes thereupon, said false bottom strip having a cigarette receiving groove at the forward lower end thereof and a depending flange at the rear end, a tongue extending inwardly from the upper rear end of said drawer and having a lateral projection at the end thereof, the flange formed at the end of said false bottom strip having an opening therein for receiving said tongue slidably therethrough, said false bottom flange and tongue projection engaging to limit opening movement of said false bottom, and a catch formed at the upper rear end of said drawer and engaging said false bottom flange just prior to full closure of said false bottom to jar the same to move a cigarette into said groove.

4. A cigarette dispenser comprising a channel shaped housing, a drawer slideable in said housing, a back member for said drawer having a central catch and a pair of tongues struck out therefrom, said tongues having laterally projecting flanges at the free ends thereof, a false bottom formed from a single sheet and including a downturned flange at the rear end thereof having openings therein slidably receiving said tongues and a cigarette receiving groove at the forward end thereof, said flanges of said tongues and false bottom engaging to limit the relative movement of said false bottom and drawer, whereupon when said false bottom is pulled further said drawer is pulled from said housing for refilling with cigarettes or cleansing thereof, said false bottom having a projection engaging said drawer just prior to full closure to jar a cigarette into said groove, and said catch being engageable with said downturned flange to retain said false bottom in closed position and also jarring said false bottom for further agitation of the cigarettes thereupon.

5. A cigarette dispenser comprising a channel shaped housing, a drawer slideable in said housing, a back member for said drawer having a tongue struck out therefrom to project into the interior of said drawer, said tongue having a laterally projecting flange at the free end thereof, a false bottom longitudinally slideable in said drawer and including a flange at the rear end thereof having an opening therein slidably receiving said tongue and a cigarette receiving groove at the forward end thereof, said flange of said tongue and said flange of the false bottom engaging to limit the relative movement of said false bottom and drawer, whereupon when said false bottom is pulled further said drawer is pulled from said housing for refilling with cigarettes or cleansing thereof.

6. A cigarette dispenser comprising a channel shaped housing, a drawer slideable in said housing, a back member for said drawer providing a central catch and a pair of tongues, said tongues having downturned flanges at the free ends thereof, a false bottom for said drawer longitudinally movable therein and including a downturned flange at the rear end thereof having openings therein slidably receiving said tongues and a cigarette receiving groove at the forward end thereof, said groove being exposed by initial movement of said false bottom relative to said drawer, said catch engaging said downturned flange of said false bottom to yieldingly retain said false bottom within said drawer, said flanges of said tongues and false bottom engaging to limit the relative movement of said false bottom and drawer, whereupon when said false bottom is pulled further said drawer is pulled from said

housing for refilling with cigarettes or cleansing thereof.

7. A cigarette dispenser comprising a channel shaped housing, a drawer slideable in said housing, a back member for said drawer providing a central catch and a pair of tongues, said tongues having downturned flanges at the free ends thereof, a false bottom for said drawer including a downturned flange at the rear end thereof having openings therein slidably receiving said tongues and a cigarette receiving groove at the forward end thereof, said flanges of said tongues and false bottom engaging to limit the relative movement of said false bottom and drawer, whereupon when said false bottom is pulled further said drawer is pulled from said housing for refilling with cigarettes or cleansing thereof, and said catch serving to retain said false bottom in closed position due to engagement with said false bottom flange and also jarring said false bottom flange for moving a cigarette into said groove upon full closure of said false bottom.

8. A device for dispensing generally cylindrical articles comprising a container having an apertured front wall, an article supporting tray movably mounted in said container for linear movement through said aperture of the front wall, means on said tray for moving a single article out of said container through said aperture, a tongue and a catch secured to said container and projecting into the interior thereof, a projecting flange on said tray having an aperture proportioned to slidably receive said tongue, whereby said tongue imparts a guiding action to the movements of said tray, a lateral projection on the free end of said tongue engageable with the aperture defining portions of said flange to limit outward movement of said tray from said container, and an end portion of said catch constructed and arranged to frictionally engage said projecting flange to retain said tray in its fully inserted position in said container.

9. The combination defined in claim 8 wherein said container is formed of thin walled metal and said tongue and said catch are formed integrally with the back wall of said container.
